(57) **CLAIM**

The ornamental design for a button cell, as shown and described.

DESCRIPTION

FIG. 1 is a top perspective view of a button cell showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a cross-sectional view taken along line 8-8 of FIG.

6.

The broken lines in the drawings illustrate portions of the button cell which form no part of the claimed design.

1 Claim, 8 Drawing Sheets
